CLAIM

The ornamental design for a dressing table, as shown and described.

DESCRIPTION

FIG. 1 is a perspective view of a dressing table showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is an enlarged view of the first selected portion in FIG. 1;

FIG. 8 is an enlarged view of the second selected portion in FIG. 1;

FIG. 9 is an enlarged view of the selected portion in FIG. 2; and,

FIG. 10 is an enlarged view of the selected portion in FIG. 3.

The dash-dot broken lines in the drawings illustrate boundary lines of an enlarged view of the dressing table and form no part of the claimed design. The dot-dot broken lines in the drawings illustrate portions of the dressing table that form no part of the claimed design.

1 Claim, 10 Drawing Sheets
